(57) **CLAIM**

The ornamental design for a butterfly-shaped baking cup, as shown.

DESCRIPTION

FIG. 1 is a top perspective view of the butterfly-shaped baking cup, showing the present design;

FIG. 2 is a top plan view of the present design;

FIG. 3 is a bottom plan view of the present design;

FIG. 4 is a left elevation view of the present design;

FIG. 5 is a right elevation view of the present design;

FIG. 6 is a rear elevation view of the present design; and,

FIG. 7 is a front elevation view of the present design.
